UNITED STATES PATENT OFFICE.

JOSEF HUTTER, OF NEW YORK, N. Y.

WALL-PLUG.

1,176,456.

Specification of Letters Patent. Patented Mar. 21, 1916.

Application filed June 24, 1915. Serial No. 36,043.

To all whom it may concern:

Be it known that I, JOSEF HUTTER, a subject of the Emperor of Austria-Hungary, and a resident of New York, in the county 5 of New York and State of New York, have invented certain new and useful Improvements in Wall-Plugs, of which the following is a specification.

This invention relates to improvements 10 in means for securing objects upon the face of blank walls comprised of cement, mortar, brick, stone or the like, non-receptive of common fastenings, as screws or nails.

The objects of the invention are, first, to 15 provide a firmly secured anchorage, rigidly set in a suitable opening formed in the wall to contain the device.

A second object is to provide, as a commercial product, such devices in forms ready 20 for immediate application and use at a moderate cost.

These objects are attained by the novel construction and combination of parts, hereinafter described and shown in the annexed 25 drawing, forming an essential part of this specification, and in which:—

Figure 1 is a side elevational view of a fragmentary portion of brick wall, showing the anchorage in position. Fig. 2 is a front 30 view of one form of the assembled anchorage. Fig. 3 is a sectional view, taken on line 3—3 of Fig. 2, showing the block expanded. Fig. 4 is a partial sectional and perspective view of the block. Fig. 5 is a 35 perspective view of the wedge or plug, and Fig. 6 is a perspective view of the tubular retaining bolt drawn to a larger scale.

In the application of the device it is necessary to form an opening in the wall by 40 means of a chisel or other suitable tool, the opening to have a cross section as near as possible to that of the block 10 and of such depth that the block may be received wholly within; it will be understood that while the 45 block is shown cylindrical and preferred in that shape that the exact form is immaterial and that the size or proportions may be varied to suit conditions.

The block 10 is preferably made of soft 50 wood, the grain of which is lengthwise for reasons well understood. Extending across one end is a V shaped opening 11, the converging beveled walls 12 of which meet at approximately two thirds of the entire length of the block, from the front or outer 55 end, where the distance across from side

to side of the walls is at least equivalent to the thickness of the edges 13 of the wedge or plug element 14. This plug, preferably made of harder wood, is rectangular in 60 shape, the width of the faces 15 being substantially equivalent to the diameter of the block 10, and its length such as to extend slightly beyond the block when inserted. An opening 16 extends through the longitudinal center of the plug 14 for the reception of a screw or similar fastening for the object supported. Axially of the block 10 is a similar opening 18, in register with the opening 16, and contained in it is an internally threaded, tubular bolt 19, the head 20 of which is against the back or inner end of the block 10, and prevented from turning by means of spurs 21 formed with the head. 75

In operation, a suitable aperture having been made in the wall, the block 10 is inserted, and the end of the plug 14 entered in the wedge shaped opening 11; the plug is then driven into the block, causing it to split 80 and the two sides be forced apart in such manner as to firmly engage with the interior walls of the opening, forming a secure anchorage for the support of any objects attached to the plug. It will be understood 85 that forcing the block asunder causes it to assume a slightly conical shape, the base and the fibers of the wood, both of the block and plug, are compressed to such an extent as to remain fixed in position. Also 90 that the tubular bolt 19 will extend well into the opening 16 of the plug and present adequate means for engaging suitable fastenings therewith. Thus it will be seen that the device offers a very convenient and 95 satisfactory means for securing articles to walls, that can be applied without the employment of an artisan and which is far superior to the common and uncertain attempts at driving a nail into walls of the 100 character mentioned.

Having thus described the invention and indicated the manner of its application and use, what I claim as new and desire to secure by Letters Patent, is:—

In a device of the class described, the combination with a compressible fibrous cylinder having a wedge-shaped opening extending transversely across one end, and a rectangular plug adapted to be forced into the mentioned opening through said cylinder, said plug having a central longitudinal passage 110

therethrough, an internally screw-threaded sleeve extending into said passage from the rear, a flanged head formed with said sleeve, said head extending laterally beyond the edges of said plug, and spurs in said flange adapted to engage the inner end of said cylinder.

Signed at New York, in the county of New York and State of New York this ninth day of June A. D. 1915.

JOSEF HUTTER.
